UNITED STATES PATENT OFFICE.

FRANKLIN F. BRADLEY, OF CHICAGO, ILLINOIS, ASSIGNOR TO BRADLEY & VROOMAN COMPANY, OF CHICAGO, ILLINOIS, A CORPORATION OF ILLINOIS.

HANGER.

1,226,856.

Specification of Letters Patent. Patented May 22, 1917.

Application filed October 5, 1916. Serial No. 123,828.

To all whom it may concern:

Be it known that I, FRANKLIN F. BRADLEY, citizen of the United States, residing at Chicago, in the county of Cook and State of Illinois, have invented a certain new and useful Improvement in Hangers, of which the following is a full, clear, concise, and exact description, reference being had to the accompanying drawings, forming a part of this specification.

My invention relates to hangers that are employed for the purpose of suspending hollow objects and includes closures upon the hangers for closing the hollow objects suspended by the hangers against the inflow of liquid whereby the device of my invention is particularly serviceable when employed for suspending hollow objects in dipping vats. Hangers of my invention are of particular service in suspending the head and foot pieces of bedsteads that are formed of tubing since by means of my invention the inflow of paint or sizing into the open bottom ends of the tubular bed posts may be prevented when the head or foot pieces of which these posts form parts are immersed in paint or sizing contained in dipping vats.

In the preferred embodiment of my invention the closures also take part in supporting the hollow objects to be suspended and in such case are in the form of plugs that are preferably conical whereby these plugs may readily be entered in the lower and open ends of the posts into which they are inserted practically to seal the bed posts.

Hitherto hangers have been employed for suspending the head and foot pieces of bedsteads formed of tubing that permitted the inflow of paint or sizing into the hollow tubular bed posts at the lower ends thereof, paint or sizing finding its way into other tubing portions united with the posts. Prior hangers permitted paint or sizing to enter the open lower ends of tubular bedsteads thereby causing wastage of the paint or sizing trapped in the bed posts, this trapped paint or sizing also frequently exuding from the bed posts and the joints in the tubing connected therewith.

I will explain my invention more fully by reference to the accompanying drawing illustrating the preferred embodiment and one use of the invention and in which drawing Figure 1 is a perspective view illustrating a head or foot piece of a bedstead sus-

pended by means of hangers of my invention; Fig. 2 is a perspective view of the preferred form of hanger; and Fig. 3 is a longitudinal sectional view of a tubular bed post shown in conjunction with a hanger of my invention in supporting relation thereto.

Like parts are indicated by similar characters of reference throughout the different figures.

Each hanger illustrated includes a gripping or suspending bar 1 that may be grasped by the hands and which bar desirably has integral continuations 2 and 3 extending angularly thereof from the same side of the bar. The continuation 2 of the gripping bar desirably terminates in a semi-circular hook 4 of a diameter which will freely accommodate a bed post 5 or other object to be suspended. The gripping bar continuation 3 desirably also terminates in a hook-like formation 6 provided with a closure 7 for the purpose of substantially closing the lower end of the bed post 5 so that liquid paint or sizing 8 in the dipping vat 9 will not readily enter the post and other hollow parts of the bed portion being dipped into the paint or sizing. The closure 7 preferably is constructed to enter the lower and open end of the bed post or tube 5 to close this end during the dipping operation, in which event the hook 6 desirably lies in a plane that is angular to and preferably substantially perpendicular to the plane of the hook 4, the plane of this latter hook being angular to and preferably substantially perpendicular to the gripping bar 1 while the plane of the hook 6 is disposed substantially in the direction of the gripping bar 1. By causing the closure to enter the bed post such closure may also act as a part of the hanger proper in that the hanger performs its suspending function in part through the intermediation of said closure. In order that the closure may readily enter the open end of the bed post and may be easily brought into engagement with the lower end of the bed post throughout the circle thereof, I make the closure in the form of a conical plug or stopper tapering away from the base of the hook 6. The penetrating portion of the hook 6 upon which the conical plug or stopper 7 is disposed projects toward the hook 4 and is preferably straight and is desirably close enough in alinement with the center of the semi-circu-

105

110

lar hook 4 to enable this latter hook to co-operate with the bed post suspended by the hanger to bring the stopper or plug 7 into full engagement with the lower end of the bed post practically to seal the same against the inflow of paint or sizing. The plug 7 is preferably in tight engagement with the hook 6 carrying it so that the structure may be simple while at the same time permitting the plug to act as a part of the hanger structure.

In Fig. 1 I have shown two hangers of my invention, these being right and left hangers, each in engagement with a hollow bed post 5 at a side of a head or foot portion of a bedstead that is to be dipped, the closure 7 forming a part of each hanger entering the lower end of the bed post engaged thereby sufficiently to close the lower end of such post against the inflow of paint or sizing, the upper end of the bed post being closed by the cap piece or other part 10 forming a permanent portion of the head or foot piece and which post is elsewhere closed against the inflow of paint as will be readily understood by those familiar with the construction of bedsteads formed of tubing.

While each hanger desirably includes two hook portions 4 and 6 that are permanently united by gripping bar 1, the invention is not to be limited to such a construction.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A hanger for hollow objects including a suspending bar; an object supporting hook extending from one side of the suspending bar, the plane of this hook being angular to the suspending bar; a second object sup-

porting hook whose free end projects toward the first hook and which free end carries a conical closure plug for hollow objects and tapering toward the first hook.

2. A hanger for hollow objects including a suspending bar; an object supporting hook extending from one end of the suspending bar, the plane of this hook being angular to the suspending bar; a second object supporting hook whose free end projects toward the first hook and which free end carries a closure plug for hollow objects and tapering toward the first hook.

3. A hanger for hollow objects including a suspending bar; an object supporting hook extending from one side of the suspending bar, the plane of this hook being angular to the suspending bar; a second object supporting hook whose free end projects toward the first hook and which free end carries a closure plug for hollow objects.

4. A hanger for hollow objects including a suspending bar; an object supporting hook extending from one end of the suspending bar, the plane of this hook being angular to the suspending bar; a second object supporting hook whose free end projects toward the first hook and which free end carries a closure for hollow objects.

5. A hanger for hollow objects including a suspending bar; object supporting hooks, one at each end of the bar; and a closure plug for hollow objects carried by one of the hooks.

6. A hanger for hollow objects including a suspending bar; object supporting hooks, one at each end of the bar; and a closure for hollow objects carried by one of the hooks.

In witness whereof, I hereunto subscribe my name this twenty-eighth day of September, A. D. 1916.

FRANKLIN F. BRADLEY.
